CLAIM

The ornamental design for a combined electrical wiring
raceway and outlet housing, as shown.

DESCRIPTION

FIG. 1 is a top, front, and right side perspective view of
a combined electrical wiring raceway and outlet hous-
ing showing our new design;

FIG. 2 is a top, rear, and left side perspective view
thereof;

FIG. 3 is a top plan view thereof;

FIG. 4 is a left side elevational view thereof.

FIG. 1

FIG. 2
